(57) **CLAIM**

The ornamental design for a storage drawer cabinet, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a storage drawer cabinet embodying our new design;

FIG. 2 is a left side profile view of the storage drawer cabinet of FIG. 1;

FIG. 3 is a right side profile view of the storage drawer cabinet of FIG. 1;

FIG. 4 is a front elevational view of the storage drawer cabinet of FIG. 1;

FIG. 5 is a rear elevational view of the storage drawer cabinet of FIG. 1;

FIG. 6 is a top plan view of the storage drawer cabinet of FIG. 1;

FIG. 7 is a perspective view of an alternative embodiment of a storage drawer cabinet embodying our new design, with unclaimed portions of the storage drawer cabinet shown in broken lines;

FIG. 8 is a left side profile view of the storage drawer cabinet of FIG. 7;

FIG. 9 is a right side profile view of the storage drawer cabinet of FIG. 7;

FIG. 10 is a front elevational view of the storage drawer cabinet of FIG. 7;

FIG. 11 is a rear elevational view of the storage drawer cabinet of FIG. 7; and,

FIG. 12 is a top plan view of the storage drawer cabinet of FIG. 7.

The broken lines shown are for illustrative purposes only and form no part of the claimed design.
